DESIGN.

W. LIES.

END FRAME FOR A BEDSTEAD.
APPLICATION FILED JUNE 7, 1921.

60,780.

Patented Mar. 28, 1922.

Inventor

WILLIAM LIES

By his Attorney

Chas. G. Lee

UNITED STATES PATENT OFFICE.

WILLIAM LIES, OF BROOKLYN, NEW YORK, ASSIGNOR TO GREENPOINT METALLIC BED COMPANY, OF BROOKLYN, NEW YORK, A FIRM COMPOSED OF DAVID FRANK, JOHN TROUNSTINE, AND WILLIAM LIES.

DESIGN FOR AN END FRAME FOR A BEDSTEAD.

60,730.

Specification for Design.

Patented Mar. 28, 1922.

Application filed June 7, 1921. Serial No. 475,738. Term of patent $3\frac{1}{2}$ years.

To all whom it may concern:

Be it known that I, WILLIAM LIES, a citizen of the United States, residing at Brooklyn, in the county of Kings and State of New York, have invented a new, original, and ornamental Design for an End Frame for a Bedstead, of which the following is a specification, reference being had to the

accompanying drawing, forming a part thereof, and which presents a perspective view of an end frame for a bedstead embodying my design.

I claim:

The ornamental design for an end frame for a bedstead, as shown.

WILLIAM LIES.
